TRUSS

Wilbert C. Pfahl, Silver Lake, Ohio

Application July 13, 1946, Serial No. 683,521

3 Claims. (Cl. 128—106)

1

This invention relates to trusses and particularly relates to a device for attaching a truss pad to a truss frame.

An object of the present invention is to provide an improved device for attaching truss pads to a supporting frame or spring, wherein after angular adjustment is made with respect to the frame the pad may be locked in adjusted position in such a way that it cannot be tampered with or accidentally misadjusted.

Another object of the invention is to provide a truss pad attachment of the character described which is adapted to be supplied in assembled condition and to have the angular adjustment made without taking the attaching assembly apart.

Other objects of the invention will be manifest from the following brief description and the accompanying drawings.

Of the accompanying drawings:

Figure 1 is a front perspective view of a truss embodying the features of the improved attaching device of the invention.

Figure 2 is a fragmentary front elevation on an enlarged scale, of a frame having a truss pad attached thereto.

Figure 3 is a cross-section taken substantially on the line 3—3 of Figure 2.

Figure 4 is a cross-section taken substantially on the line 4—4 of Figure 2.

Figure 5 is a view taken substantially on the line 5—5 of Figure 4, illustrating the inner side of the truss pad attaching plate.

Figure 6 is a view similar to Figure 2, but illustrating a truss pad attached to a different style of supporting frame or spring.

Referring particularly to Figure 1, there is illustrated a truss 10 of the type used for the treatment of hernias or ruptures, the same including essentially a metal supporting frame or spring 11, adapted to fit around the abdomen of the wearer with rearwardly free ends 12 and 13 adjustably connected, as by means of a suitable strap 14, truss pads 15, 15 being adjustably mounted at the front of the spring frame to be in position for holding the hernia or rupture. The truss pads 15, 15 may be of sponge rubber or other suitable material, formed in different shapes and sizes as required for particular conditions of truss wearers, the same being laterally and angularly adjustable with respect to spring frame 10 by means of an attaching unit or assembly 16 thereon.

Referring particularly to Figures 2 to 5 the attaching unit 16 may include a backing plate

17 adapted to be releasably secured to pad 15, by means of screws 19, 19 received through spaced apertures 20, 20 in the plate and threaded into a metal insert 21 vulcanized or otherwise embedded in the rubber of pad 15. To provide for the aforementioned lateral and angular adjustment of pad 15 relatively of frame 11, the plate 17 is provided centrally thereof with a relatively large opening 22, and outer and inner disc-like 5 clamping elements 23 and 24, respectively, which are of greater diameters than that of the opening 20 for spanning between the edge portions thereof, at opposite sides of the plate (see Figures 3, 4 and 5). For laterally adjustably securing 10 the attaching unit 16 and the pad thereon to the spring frame 11, an arched metal bridge 18 is engageable across the inner side of the frame and screws 29, 29 may be received through spaced apertures 18a, 18a therein to be outwardly of opposite edges of the frame, these screws then extending through spaced apertures 25, 25 in outer disc 23, through the large plate aperture 22 and being screwed into registering threaded holes 28 15 in the inner disc 24. Locking screws 30, 30 for the clamping discs are similarly received from the inner side of the backing plate 17, through spaced apertures 27, 27 in the inner disc 24, circumferentially spaced from the threaded apertures 28, 28, and then extended through the plate 20 aperture 22 and threaded into the correspondingly aligned holes 26, 26 in the outer disc 23. The screws 29 and 30 are diametrically oppositely spaced in such a manner that engagement 25 thereof with the edge portions of the plate aperture 22 may be utilized for maintaining and guiding the clamping plates in centered or concentric relation with respect to said opening when the clamping plates are angularly or rotatably adjusted. The spring frame 11, if desired, may 30 be covered with rubber, plastic or other resilient material, which covering will provide extra tension when the screws 29 are tightened to clamp the discs together.

In the use or operation of the attaching unit 45 16, to fit each truss pad 15 to suit the particular condition of a hernia or rupture sufferer, the pad 15 may be supplied with the attaching unit 16 completely assembled thereon but with the inner screws 30, 30 adjusted to apply relatively 50 light clamping pressure to the discs 23 and 24 to permit angular or rotational adjustment thereof with respect to the backing plate 17, but this clamping pressure being sufficient to retain the clamping disc in any given position of such angular or rotational adjustment. With the pad

and attaching units thereof so assembled, one of the screws 29 may be removed while the other is loosened to permit engagement of the bridge 18 over the spring frame 11 in desired laterally adjusted position thereof, as best shown in Figure 1, after which the two screws 29 may be tightened to a degree which prevents lateral movement from said adjusted position without applying additional clamping action to the discs 23 and 24. When the pad has thus been laterally adjusted it may be turned relatively of the clamping discs and spring frame, as guided by the clamping screws 29 and 30 engaging the inner edge portions of the plate aperture 22, as for example, from the full line to the chain-dotted line positions illustrated in Figure 2, or otherwise as best suited for the comfort of the individual truss wearer. When the pad 15 is suitably located with respect to the spring frame 11 the outwardly presented adjusting screws 29 may be tightened to apply clamping pressure to the discs against the backing plate 17, firmly to hold the pad in both the laterally and angularly adjusted positions. When once the pads have been thus properly fixed in desired adjustment with respect to the spring frame 11 the screws 19, 19 may be removed to permit removal of the pad 15 from plate 17, thereby to expose the inner face of the plate and permit tightening of the inner locking screws 30, 30 for additionally clamping the discs 23 and 24 together. When this locking adjustment has been accomplished the pad 15 may again be secured to the backing plate 17 by means of the screws 19.

Thus it will be seen that, because the locking screws 30, 30 are concealed between the pad 15 and backing plate 17, they cannot be reached for tampering with the lateral or angular adjustment of the pad with respect to the spring frame 11 after adjustments have been made, as for example, by a skilled technician. Similarly the locking screws assure that the pad will not become accidentally misadjusted. In case the screws 19, 19 are inaccessible because of the location of the spring 11, they may be exposed for removal of the pad 15 with the unit 16 thereon, by removal of one or both of the bridge-plate screws 29, without necessarily disturbing the aforementioned angular adjustments.

In Figure 6 there is illustrated a method of attaching a pad 15 and attaching unit 16 thereof to a type of spring supporting frame 35 which is provided with an elongated slot 36 used for attaching purposes. In this particular type of frame the bridge 18 is eliminated, the spaced screws 28, 29 being received through the slot 36 and tightened substantially as previously described to clamp the unit 16 to the frame. The use or operation of the device of Figure 6 is otherwise as before, like parts being given like numerals previously referred to.

Modifications of the invention may be resorted to without departing from the spirit thereof or the scope of the appended claims.

What is claimed is:

1. An attachment for truss pads or the like to be mounted on a truss frame or similar supporting part, comprising a backing plate having a circular opening therein, means for releasably securing said plate to a truss pad, outer and inner disc-like elements of greater size than said plate opening for spanning between the edge portions thereof at opposite sides of the plate, adjustable means operable from the inner side of said plate for clamping said elements together against said

opposite sides of the plate in various rotatably adjusted positions relatively of the plate about the center of said opening thereof, and means on said outer element independently of said adjustable means for securing the attachment to said supporting part.

2. An attachment for truss pads or the like to be mounted on a truss frame or other supporting part, comprising a backing plate having a circular opening therein, means for releasably securing said plate to a truss pad, outer and inner disc-like elements of greater size than said opening for spanning between the edge portions thereof at opposite sides of the plate, said outer element having diametrically spaced apertures and diametrically spaced threaded holes circumferentially spaced therefrom, said inner element having spaced apertures and threaded holes for cooperative alignment with the spaced threaded holes and spaced apertures, respectively, of said outer element, screw means received through said spaced apertures of said inner element and threaded into the corresponding threaded holes of said outer element to be operable from the inner side of said plate to clamp the elements together against said opposite sides of the plate in various rotatably adjusted positions relatively of the plate about the center of said opening, and screw means received through the spaced apertures of said outer element and threaded into the corresponding threaded holes of said inner element for additionally clamping the elements together and adapted to secure the attachment to said supporting part.

3. An attachment for truss pads or the like to be mounted on a truss frame or other supporting part, comprising a backing plate having a circular opening therein, screw means for releasably securing said plate to a truss pad, outer and inner disc-like elements of greater size than said opening for spanning between the edge portions thereof at opposite sides of the plate, said outer element having diametrically spaced apertures and diametrically spaced threaded holes circumferentially spaced therefrom, said inner element having spaced apertures and threaded holes for cooperative alignment with the spaced threaded holes and spaced apertures, respectively, of said outer element screw means received through said spaced apertures of said inner element and threaded into the corresponding threaded holes of said outer element to be operable from the inner side of said plate to clamp the elements together against said opposite sides of the plate in various rotatably adjusted positions relatively of the plate about the center of said opening, and screw means received through the spaced apertures of said outer element and threaded into the corresponding threaded holes of said inner element for additionally clamping the elements together and adapted to secure the attachment to said supporting part, said element screw means being diametrically spaced to be substantially closely adjacent the edge portions of said plate opening for guiding said rotatable adjustment of said elements.
